US00D973437S

(12) **United States Design Patent** (10) **Patent No.:** **US D973,437 S**
(45) **Date of Patent:** **** Dec. 27, 2022**

(54) **LID OF A BATTERY-POWERED PORTABLE BLENDER**

(71) Applicant: **BlendJet Inc.**, Benicia, CA (US)

(72) Inventor: **Ryan Michael Pamplin**, San Juan, PR (US)

(73) Assignee: **BlendJet Inc.**, Benicia, CA (US)

(**) Term: **15 Years**

(21) Appl. No.: **29/759,294**

(22) Filed: **Nov. 20, 2020**

(51) **LOC (13) Cl.** **07-04**

(52) **U.S. Cl.**
